UNITED STATES PATENT OFFICE.

BIRGER FJELD HALVORSEN, OF CHRISTIANIA, NORWAY.

EXPLOSIVE.

1,375,588.

Specification of Letters Patent. Patented Apr. 19, 1921.

No Drawing.

Application filed December 4, 1919. Serial No. 342,518.

To all whom it may concern:

Be it known that I, BIRGER FJELD HALVORSEN, a subject of the King of Norway, residing at Christiania, Norway, have invented certain new and useful Improvements in Explosives; and I do hereby declare the following to be a full, clear, and exact description of the invention, such as will enable others skilled in the art to which it appertains to make and use the same.

This invention has for its object an explosive consisting of a derivative of urea.

As is known organic nitro-compounds have attained a very extended use as explosives.

The most valuable explosives of this type are those obtained from fats and from tar products as united material.

An object of the present invention is to make the manufacture of explosives independent of these materials, which in times of international conflicts are not easily available in sufficient quantities besides being strongly in demand for other purposes.

The invention is based upon the observation that the nitro-derivatives of urea such as for example the compound

are very strong and brisant explosives with great power of resistance against blows and shocks and in accordance with this observation the present invention has for its object the employment of the nitroderivative of urea as an explosive.

As is known the nitro-urea

behaves as an acid. One of its hydrogen atoms may be interchanged with radicals such as metals or organic bases. The compounds so obtained may also be used as explosives. The nitro compounds in question 45 may be used as explosives alone or in mixtures with other substances comprising also other explosives.

Nitro-urea may for instance be obtained by treating urea nitrate with concentrated 50 sulfuric acid at a low temperature. The urea nitrate can be easily obtained with a good output from calcium cyanamid by lixiviation with water, precipitation in the resulting solution with carbon dioxide to remove the lime and treatment of the filtrate with nitric acid either before or after the filtrate has been evaporated. It is thus possible to produce a brisant explosive from calcium cyanamid nitric acid and sulfuric 55 acid as raw materials.

Claims.

1. As a new article of manufacture, a commercial explosive comprising an explosive nitroderivative of urea.

2. A commercial explosive comprising a nitro urea radical in chemical combination with an additional radical.

3. An explosive comprising an explosive nitroderivative of urea in mechanical mixture with other substances.

In testimony that I claim the foregoing as my invention, I have signed my name in presence of two subscribing witnesses.

BIRGER FJELD HALVORSEN.

Witnesses:

INGARD HALVORSEN,
JOHN PETERSEN.
